UNITED STATES PATENT OFFICE

MILTON MARKLEY, OF HARRISBURG, PENNSYLVANIA, ASSIGNOR TO THE RAIL JOINT COMPANY, OF NEW YORK, N. Y., A CORPORATION OF NEW YORK

CONSTRUCTION FOR REHABILITATING RAIL JOINTS

Application filed January 22, 1930. Serial No. 422,627.

This invention relates to a novel means for rehabilitating worn rail joints and possesses utility not only in connection with the head-contact type of rail joint, but also in connection with the headfree type of rail joint 5 wherein the bar has a loading engagement at and in the head fillet of the rail.

To that end the invention primarily has in view a practical and effective means for 10 restoring a worn rail joint in track, to proper fishing position, with proper clearances from the rail, in order that adequate adjustment may be made by the tightening of the bolt and the joint otherwise restored to full 15 operative position and effectiveness for such additional service as may be obtained from the same. In carrying out that object the invention contemplates a construction which is 20 advantageously applicable to the head-contact type of joint bar to correct the undesirable "cocking" inwardly of the bar, when worn, and in effect converting it into the headfree type of bar wherein the main loading engagement is at the head fillet of the 25 rail, while at the same time providing a construction which may be employed with equal 30 advantage in the regular headfree type of bar in order to restore the base part of the bar to a proper clearance over the rail base 35 flange so that the proper and adequate adjustment may be made in the foot of the headfree bar upon the tightening of the bolts. In other words, the present invention contemplates a reliable means for rail joints equally 40 applicable, with desirable results and advantages, for restoring to proper fishing position both the head-contact and headfree types of rail joint bars.

With these and other objects in view which 45 will be readily apparent to those familiar with the art, the invention consists in the novel features of improvement hereinafter more fully described, illustrated and claimed, and while susceptible of embodiment in various structural forms, certain preferred and practical examples of the invention, are shown in the accompanying drawings, in which:—

Figure 1 of the drawings is a vertical half-sectional view of a rail joint illustrating the

wear that occurs at the head and foot of a head-contact type of rail joint bar, due primarily to inward "cocking" thereof.

Figure 2 is a vertical half-sectional view of a rail joint illustrating that form of the 55 invention wherein a head-contact type of bar worn by inward "cocking" is restored to a new and correct fishing position, and functioning on the principle of the headfree type of bar.

Figure 3 is a side elevation of the joint with the joint bar removed to expose the 60 preferable embodiment of both the upper and lower sets of spacing plates which are used to rehabilitate the head-contact type of bar, 65 such as shown in Fig. 1.

Figure 4 is a vertical sectional half-view of a rail joint showing the wear that occurs in the foot flange of a headfree type of bar to be compensated for by the present invention 70 in order to rehabilitate such bar to proper fishing fit and clearance.

Figure 5 is a view similar to Fig. 4 showing the preferable means employed to rehabilitate the worn joint of Fig. 4.

Figure 6 is a side elevation of the joint with the joint bar removed to expose the preferable arrangement of the spacing or compensating plates used in rehabilitating a headfree joint of the type shown in Figs. 4 75 and 5.

Figure 7 is a sectional view showing a modified form of spacing or compensating plate employed beneath the foot of a headfree type of joint bar.

Figure 8 is a detail perspective of one of the lower spacing or compensating plates used in its preferable form.

Like references designate corresponding parts in the several figures of the drawings.

In carrying the invention into effect the same may be embodied in a joint bar of any conventional type, so for example there is shown in the drawings a continuous rail joint bar designated generally by the reference numeral 1 and including in its organization the bar head 2, the foot flange 3 overlying the base flange 4 of the rail R and the rail supporting base plate or base member 5 integrally united with the foot flange 3 in the 95 100

usual neck 6 formed with the spiking toe 7. These are the usual elements of a continuous joint bar, but the present invention is primarily concerned with those portions of the bar subject to wear and which when worn cause the bar to assume an incorrect position and not susceptible of being properly adjusted to maintain a tight joint. Taking for instance the illustration of Fig. 1 of the drawings, the dotted line *z* at the head of the bar indicates the wear from the undesirable "cocking" inwardly of a head-contact bar, this being the result of the outer portion of its top surface, as at *v*, wearing down to a degree where there could be no longer a proper head fishing contact with the underside of the rail head adjacent the outer edge of the latter when the bar is straightened to a correct fishing position. At the same time a head-contact bar which has been worn down and "cocked" inwardly at the head as indicated, becomes worn to a greater or less degree along the surface *z*, Fig. 1, that is, at the underside of its foot flange contiguous to and adjoining the bottom inner toe projection 8. Consequently, in order to rehabilitate a joint having a bar worn in this manner it is not only necessary to rectify or straighten the bar to a correct fishing position, but also to provide a proper bearing and clearance at the foot of the bar in order that it may effectively function as a rail joint structure even though the bar as a clearance from the outer portion of the head fishing surface of the rail as shown in Fig. 2 of the drawings.

Referring now more particularly to Fig. 2 of the drawings this drawing illustrates the worn rail joint bar of Fig. 1 rehabilitated to a correct fishing position and properly mounted and arranged so as to function mainly in the manner of the headfree type of bar wherein the loading engagement for the bar is at or adjacent the head fillet of the rail. To accomplish that desirable result in a rail joint bar of the head-contact type which has become worn in the manner indicated by the illustrative view of Fig. 1 of the drawings there are employed upper and lower sets of spacing or wear-compensating plates 9 and 10, the plates 9 being those employed for rectifying or correcting the position of the head of the bar and therefore constituting the bar head spacing plates and the plates 10 constituting the plates for restoring to proper fishing and adjusting the position of the foot of the bar and therefore properly termed the foot spacing plates. These plates are preferably made of mild steel, that is, steel milder or softer than the steel of the rail and joint bars in order to perform the dual function as spacers and wear elements.

The head and foot spacing plates 9 and 10 are, for practical purposes, preferably made in lengths shorter in length than one-half of the length of the joint bar and referring to

Figs. 2 and 3 of the drawings it will be seen that each head spacing plate 9 is interposed between the inner side of the bar head 2 and the rail web and preferably extends upwardly into the recess of the head fillet of the rail, whereby the inner side of the head of the bar takes a bearing against the said spacing plate while the upper surface of the bar head also takes a partial bearing against the underside of the rail head at a distance inwardly from the outer edge thereof because of the worn top (*v*, Fig. 1), of the bar due to the "cocking" inwardly as previously explained. Thus, the bar head is seated substantially within the rail head fillet and adjacent both sides thereof in a manner similar to the seating of the bar head in the headfree type of joint so that the loading engagement of the bar head is at a distance inwardly from the outer side of the rail head. Thus, the bar in its rectified or corrected position, with the use of the head spacing plate 9, becomes in effect a headfree structure wherein the adjustment thereof is provided for by the rotative movement of the foot of the bar over the rail base flange and in order to provide for the correct seating of the bar, particularly where worn (*z*), over the rail base flange the foot spacing plate 10 is employed which is interposed between the worn underside of the bar foot flange 3 and the upper inclined surface of the rail base flange 4. Accordingly, it will be seen that the spacing plates 9 and 10 not only compensate for the worn places at the head and foot of the bar, but also correctly restore the bar to a proper fishing position with proper clearances for further adequate adjustment.

In order to prevent longitudinal displacement or creeping of the head and foot spacing plates 9 and 10 various expedients can be resorted to, but preferably this is accomplished by providing each head spacing plate at its bottom edge with a depending locking apron adapted to extend between a pair of joint bolts and to provide each foot spacing plate 10 at its upper edge with an upwardly projecting locking apron 12 adapted to extend between two bolts and to have locking engagement therewith. Also, it will be observed that in the preferable construction each foot spacing plate 10 is an angle formation with the bottom inclined flange thereof interposed between the foot of the bar and the upper side of the rail flange and the upstanding flange thereof constituting the apron 12 which provides the lock or stop against longitudinal movement.

A further feature of practical importance in connection with the use of the restoration or spacing plates 9 and 10 is that these plates permit of the joint being restored to proper fishing position and adjustment while the joint bar is in track and without disturbing the surface of the track. That is

readily accomplished, as can be seen particularly from Fig. 3 of the drawings by merely slightly loosening the bolts of the joint and taking out one end bolt at a time which permits of slipping the plates 9 and 10 into the joint from that end and then replacing that joint bolt, and subsequently repeating the operation from the other end of the joint after which all of the bolts are fully tightened and the joint then becomes fully rehabilitated with the joint bars at both sides in correct fishing position and with proper clearances for further adjustment. Usually in rehabilitating a joint in this way the spacing or restoration plates are applied to both sides of the joint so that both joint bars will be restored to correct working positions.

The construction so far described relates to the rehabilitating of rail joints of the head-contact type, but as previously indicated the invention is clearly applicable to the restoration of worn joint bars of the headfree type. In that type of rail joint, that is, of the headfree type the said joint includes joint bars designated generally by the reference letter B and having a head portion C and the foot portion D, the head portion being provided with an inner bearing member 13 having a bearing and rotative engagement with the fillet 14 of the rail R and at this point, that is, at the head fillet, the bar has its loading engagement. In such a joint bar wherein the foot member D has a rotative movement inwardly and upwardly over the rail base flange 4 the main wear occurs at the underside of the foot member as at W and such wear is compensated for, in the present invention, by the use of a foot spacing or compensating plate 10 of the kind and type already described and subserving the same function as the said plate 10 shown in connection with the rehabilitated head-contact type of joint bar. Thus, it will be seen that with the headfree type of joint illustrated in Figs. 4 and 5 of the drawings the joint is restored to proper fishing and proper clearance by the use merely of a foot spacing plate, which is arranged as shown in Fig. 6 of the drawings to permit of the joint being rehabilitated in track in the same manner as hereinbefore described.

To illustrate the range of modification which may be resorted to in carrying forward the invention there is shown in Fig. 7 of the drawings a modified structure wherein each foot spacing plate is provided with an inwardly folded upwardly extending apron 15, which like the apron 12 previously referred to, extends between and engages the bolts at the same time the down-turned edge portion of the folded apron 15 engages the web of the rail, in such a manner as to keep it pressed outwardly toward the joint bar instead of being free to drop inwardly so as to allow the lower flange of

the plate between the rail flange and the foot of the bar to work outwardly. This action serves to assist in holding the foot spacing plate in correct operative relation with a joint bar and furthermore the folding of the said apron inwardly also serves to at least double the resistance of the apron against the bolt, since there are two thicknesses of metal provided by the apron to engage the bolt instead of one thickness. However, the greatest utility of the folded-over apron is that of serving to keep the main part of the apron outward in a substantially upright position.

Other modifications of the joint rehabilitating construction may be resorted to without departing from the invention and it will also be understood that changes in the form, proportion and minor details of construction may likewise be resorted to within the contemplation of the invention and without departure from the scope of the claims.

I claim:—

1. A rehabilitated rail joint structure including the rails, a splice bar having bearing engagement with the rail head and a clearance from the outer portion of the head fishing surface of the rail, and a wear compensating spacing member interposed between the foot of the bar and the rail flange. 90

2. A rehabilitated rail joint structure including the rails, a splice bar having its inner head projection engaging the rail and having a clearance from the outer portion of the head clearance surface of the rail and a wear compensating member interposed between the foot of the bar and the rail flange and having means preventing displacement thereof. 100

3. A rehabilitated rail joint structure including the rails, a splice bar having its inner head projection engaging the rail and having a clearance from the outer portion of the head clearance surface of the rail and a wear compensating member interposed between the foot of the bar and the rail flange and having means engaging with the joint bolts to prevent displacement thereof. 105

4. A rehabilitated rail joint structure including the rails, a splice bar having head fishing clearance from the outer portion of the rail head and a loading engagement with the rail at the head fillet thereof, and a wear compensating and restoration member interposed between the foot of the bar and the rail flange. 115

5. A rehabilitated rail joint structure including the rails, a splice bar having head fishing clearance from the outer portion of the rail head and a loading engagement with the rail at the fillet thereof, and a wear compensating and restoration plate of angle formation, one flange of said plate overlying the rail flange under the foot of the bar and the other flange of said plate having a locking engagement with the joint bolts. 125

6. A rehabilitated rail joint structure including the rails, a splice bar having head fishing clearance from the outer portion of the rail head and a loading engagement with the rail at the fillet thereof, a clearance restoration plate arranged between the head of the bar and the rail web and a clearance restoration plate arranged between the foot of the bar and the rail web.
10. 7. A rehabilitated rail joint structure including in combination the rails, clamping bolts, a joint bar having head clearance from the underside of the outer portion of the rail head and also having a bearing surface at its inside face, a plate arranged between said bearing surface and the rail web and a plate interposed between the upper side of the rail flange and the underside of the foot of the bar.
15. 8. A rehabilitated rail joint structure including the rails, joint bars, and clearance restoration plates interposed between the joint bars and the rail, each of said restoration plates being shorter in length than one-half of the length of the joint bar.
20. 9. A rehabilitated rail joint structure including the rails, joint bars, and clearance restoration plates interposed between the joint bars and the rail, each of said restoration plates being shorter in length than one-half of the length of the joint bar and insertable endwise into the joint from one end thereof.
25. 10. A rehabilitated rail joint structure including the rails, joint bars, and clearance restoration plates interposed between the joint bars and the rail, each of said restoration plates being shorter in length than one-half of the length of the joint bar and insertable endwise into the joint from one end thereof when one joint bolt is removed.

In testimony whereof I hereunto affix my signature.

MILTON MARKLEY.
